UNITED STATES PATENT OFFICE.

LOUIS W. CARROLL, OF RIVERSIDE, ILLINOIS.

TELEPHONE-RECEIVER.

1,034,200.

Specification of Letters Patent. Patented July 30, 1912.

Application filed October 24, 1910. Serial No. 588,907.

To all whom it may concern:

Be it known that I, LOUIS W. CARROLL, a citizen of the United States of America, and resident of Riverside, county of Cook, and State of Illinois, have invented certain new and useful Improvements in Telephone-
receivers, of which the following is a specification, and which are illustrated in the accompanying drawings, forming a part
10 thereof.

The invention relates to telephone receivers, and has for its object to increase the efficiency of instruments of this kind.

In its broadest aspect, the invention contemplates the use of a diaphragm, and an actuating magnet located in front of the diaphragm or upon that side of the diaphragm at which provision is also made for the emission of the sound produced by the vibration of the diaphragm. In carrying out the invention I prefer, however, to use a pair of actuating magnets, one located upon each side of the diaphragm, the coils of the two magnets being so connected that when the attractive effect of one of the magnets is increased that of the other is reduced.

A detail of the invention provides a magnet for use in front of the diaphragm, having a central aperture for the emission of sound.

In the accompanying drawings, Figure 1 is a detail central sectional view of one form of telephone receiver embodying the improvements provided by the invention; Fig. 2 is a sectional view taken on the broken line 2-2 of Fig. 1; Fig. 3 is a diagram illustrating the manner of winding and connecting the magnet coils of the structure illustrated in Figs. 1 and 2; Fig. 4 is similar to Fig. 1 but shows a different embodiment of the invention; Fig. 5 is a perspective view showing the actuating magnets employed in the form of construction illustrated in Fig. 4; and Fig. 6 is a diagram illustrating the method of winding and connecting the magnet coils of the structure illustrated in Figs. 4 and 5.

In practice the operative parts of the receiver may be inclosed within a shell comprising a body portion or hand-piece 10, and an ear-piece or cap 11, both of which are shown as resembling in external appearance the corresponding parts of telephone receivers now in use, except that the ear-piece 11 has an end opening 12 of somewhat

larger diameter than the corresponding opening in receiver shells heretofore employed. The two members 10, 11, of the shell preferably have a screw-threaded connection 13. As shown, oppositely-facing shoulders 14 and 15 are provided on the members 10, 11, and the operative parts of the receiver are clamped between these shoulders when the members of the shell 60 are screwed together. A soft iron diaphragm 16 of usual construction is employed as the sound producing medium.

In the form of construction illustrated in Figs. 1, 2 and 3 of the drawings, permanent steel magnets 17 and 18 are employed. As shown, each of these magnets takes the form of an annulus or disk having a central opening 19. The disks are preferably substantially coextensive with the diaphragm 16, 70 and both of them are so magnetized as to have one pole upon the periphery of the disk and the other pole upon the inner margin of the disk about the central opening 19. The two disks or magnets 17, 18, 80 are used upon opposite sides of the diaphragm 16, and they are oppositely magnetized in order that if the disk 17 presents a south pole adjacent the center of the diaphragm, the disk 18 will present a north 85 pole upon the opposite side of the diaphragm in line with the south pole of the disk 17.

The disks 17, 18, are separated from the diaphragm 16 on each side by a spacing 90 ring, as 20 and 21. These spacing rings are preferably made of soft iron, and each has a marginal flange or bead 22 upon its inside face whereby the margins of the diaphragm 16 may be clamped between the spacing 95 rings 20 and 21, while still leaving the diaphragm 16 free to vibrate for nearly its whole extent.

A soft iron tube or nipple 23 is fitted within the central opening 19 of each of the disks 17, 18. These nipples project inwardly from the face of the disks toward the diaphragm 16. Magnet coils 24, 25, are wound about the inwardly-projecting ends of the tubes or nipples 23. These coils are 105 preferably connected by a wire 26, extending beyond the margins of the diaphragm 16, as by being laid in grooves 27, 28, formed radially in the faces of the spacing rings 20 and 21, and the coils are oppositely wound, 110 as shown in diagram in Fig. 3. The terminals 29, 30, of the coils 24, 25, are laid into

radial grooves 31, 32, in the spacing rings 20 and 21, and extend to binding posts, as 33, 34. These binding posts are conveniently mounted upon a lug 35, formed on the 5 inner wall of the handle portion 10 of the shell. Leading-in wires 36, 37, preferably entering the chamber of the shell through the rear end (not shown) of the handle portion 10, are also connected to the binding 10 posts 33, 34.

In assembling the parts of the receiver, a layer of felt, or other cushioning material 38, is laid upon the shoulder 14 to form a cushioned seat for the disk 17, and the several parts are then clamped together upon 15 this seat by screwing the ear-piece 11 onto the body portion or handle 10 of the shell.

In the form of construction illustrated in Figs. 4, 5 and 6 of the drawings, no permanent magnets are employed, but in lieu 20 thereof soft iron disks 39, 40, adapted to be continuously magnetized by a direct current, are used. As in the form of construction illustrated in Figs. 1, 2 and 3 of the drawings, the disks 39 and 40 are each substantially coextensive with the diaphragm 16, and they are located upon opposite sides of the diaphragm. Each of the disks has a central opening 41, and about this opening 25 the disks are so formed as to provide an inwardly-facing tubular shank or stem 43 at the center of each disk, and an annular groove or channel 42 about the stem 43. At the margins of the disks 39, 40, there are in- 30 standing beads or flanges 44, 45, for engaging the opposite faces of the diaphragm 16 adjacent its margins.

For continuously magnetizing the disks 39, 40, whereby their instanding tubular 40 stems 43 will present opposite poles to the diaphragm 16, magnet coils 46, 47, each preferably consisting of a comparatively large number of turns of relatively coarse wire, are laid into the annular grooves or 45 channels 42. Preferably these coils fill the channels 42 for the greater portion of their depth, but leave the tips of the tubular stems 43 uncovered for receiving a second coil, as 48, 49. The latter coils each preferably 50 consist of a comparatively small number of turns of relatively fine wire.

The coils 46, 47, and the coils 48, 49, are connected, as by means of wires 50 and 51, extending over the margins of the diaphragm 16, as by being laid into grooves or notches 52, 53, in the disks 39 and 40. As most clearly shown in Fig. 6 of the drawings, the coils 46 and 47 are wound in the same direction, but the coils 48, 49, are preferably 55 oppositely wound, the coil 48, as shown, being wound in the same direction as the coils 46 and 47. The coils 46 and 47, and the coils 48 and 49, are preferably connected in parallel or branch circuits. This 60 is conveniently effected by connecting the 65

terminals, as 54 and 55, of the coils 46 and 47 with the respective terminals, as 56 and 57, of the coils 48 and 49, as shown at the junction points 58 and 59.

Binding posts 62 and 63 are preferably 70 employed for receiving the leading-in wires 36 and 37. As in the construction shown in Fig. 1 of the drawings, the binding posts are conveniently mounted upon a lug 64, formed upon the inside wall of the handle 75 portion 10 of the shell. Connections 60 and 61 lead from the junction points 58 and 59 to these binding posts 62 and 63, respectively. When the parts are assembled the margins 80 of the diaphragm 16 are clamped between the margins of the disks or magnets 39 and 40, and all of the parts are firmly bound together by screwing the cap portion 11 of the shell onto the handle or body portion 10.

In both of the forms of construction illustrated, the central portion of the disk or magnet, as 18 and 40, located in front of the diaphragm 16, is exposed through the central opening 12 of the cap 11, thereby permitting the sounds produced by the vibration 85 of the diaphragm 16 to escape through the tubular members 23 and 43. By locating magnets of opposite polarity upon the two sides of the diaphragm, the diaphragm is not permanently deflected by magnetic 90 attraction. When the undulating current flows through the magnet coils, as 24, 25, and 48, 49, the balance of attractive force of the magnets located upon the two sides of the diaphragm is disturbed, and the dia- 95 phragm is accordingly vibrated. 100

The arrangement is such that when the attractive force of one of the magnet poles, as 17 and 39, is augmented, the attractive force of the other magnetic pole, as 18 and 40, is diminished. By means of this construction a very slight deviation of current 105 in the magnet coils, as 24 and 25, or 48 and 49, is sufficient to cause a considerable deflection of the diaphragm 16. The deflection 110 of the diaphragm 16 is further enhanced by the excitation of magnetic lines of force in the diaphragm itself, because of the location of the oppositely wound coils 24, 25, or 48, 49, upon opposite sides of the diaphragm. 115

Because of the relatively high resistance of the coils 48, 49, provided in the form of construction illustrated in Figs. 4, 5 and 6 of the drawings, a continuous direct current will flow principally through the coils 46, 120 47. On the other hand, an undulating current, such as that produced by talking into a telephone transmitter of ordinary form, will flow principally through the coils 48 and 49, because of the relative impedance of the 125 coils 46 and 47.

While the operative parts of the receiver are shown as being inclosed in a shell of about the size and shape of that used for telephone receivers of the form now in very 130

common use, it is obvious that because of the compact arrangement of the actuating magnets about the diaphragm the parts may be inclosed within a shell of much less 5 length, if desired. Furthermore, in the forms of construction described there will be no changes in the distance between the magnets and the diaphragm produced by unequal expansion and contraction between the 10 parts of the shell and the metal parts of the apparatus when subjected to changes in temperature, as has been the case with many telephone receivers heretofore used.

While the magnet coils 48, 49, in the form 15 of construction illustrated in Figs. 4, 5 and 6 of the drawings are of relatively high resistance, they will, of course, receive some of the direct current. In order that the magnetic effect of the two magnet poles located 20 on opposite sides of the diaphragm 16 may be balanced when only direct current is being supplied to the receiver, the coil 46 is, therefore, preferably made of a larger number of turns than the coil 47, for the 25 reason that the coils 46 and 48 are oppositely wound, whereas the coils 47 and 49 are similarly wound. To prevent induced currents traversing the poles, as 23 and 43 of the magnets, circumferentially, these are 30 preferably divided into segments, as by saw kerfs 65 and 66.

I claim as my invention—

1. In a telephone receiver, in combination, 35 a diaphragm, a soft iron cup facing the diaphragm and substantially coextensive with it, a soft iron stem projecting centrally from the bottom of the cup toward the diaphragm, a coil of low resistance and high impedance surrounding the greater portion 40 of the stem except its tip, and a coil of high resistance and low impedance surrounding the tip of the stem, the two coils being connected in parallel.

2. In a telephone receiver, in combination, 45 a diaphragm, a soft iron cup facing the diaphragm upon each side, each of said cups being substantially coextensive with the diaphragm and the two cups being magnetically connected at their peripheries, a soft 50 iron tubular stem projecting centrally from the bottom of each cup toward the diaphragm, a coil of low resistance and high impedance surrounding the greater portion of each tubular stem except its tip, the two 55 coils being connected and similarly wound, and a coil of low impedance and high resistance surrounding the tip of each stem, the two last-named coils being connected

and being reversely wound, and the two last-named coils being connected in parallel with 60 the two first-named coils.

3. In a telephone receiver, in combination, a diaphragm, an annular trough-shaped piece of soft iron facing the diaphragm upon one side, a coil of low resistance and high impedance filling the bottom portion of the trough, and a coil of high resistance and low impedance filling the upper portion of the trough, the two coils being connected in 65 parallel.

4. In a telephone receiver, in combination, a diaphragm, an annular trough-shaped piece of soft iron facing the diaphragm upon each side, a coil of low resistance and high impedance filling the bottom portion 75 of each trough, the two coils being connected and similarly wound, a coil of high resistance and low impedance filling the upper portion of each trough, the two last-named coils being connected and reversely wound, 80 and the two first-named coils being in a parallel circuit with the two last-named coils.

5. In a telephone receiver, in combination, a diaphragm, an actuating magnet having a soft iron core and two energizing coils connected in parallel relation located on each side of the diaphragm, the two coils of one of the magnets being similarly wound and the two coils of the other magnet being 85 oppositely wound, and the several coils being so proportioned in size that when supplied with direct current from the same source the two magnets are equally but oppositely magnetized.

6. In a telephone receiver, in combination, 90 a diaphragm, an actuating magnet having a soft iron core and two energizing coils connected in parallel relation located on each side of the diaphragm, the two coils of one of the magnets being similarly wound and 95 the two coils of the other magnet being oppositely wound, and the several coils being so proportioned in size that when supplied with direct current from the same source the two magnets are equally but oppositely 100 magnetized, one of the coils of each of the magnets being adapted to be traversed by voice currents while the other coil of each magnet possesses impedance to restrict the 105 flow of voice currents, the two coils adapted 110 to be traversed by voice currents being oppositely wound.

LOUIS W. CARROLL.
